UNITED STATES PATENT OFFICE.

CALEB C. REID, OF NEW BURNSIDE, ILLINOIS.

RAILWAY-CROSSING SIGNAL.

1,299,383.

Specification of Letters Patent.

Patented Apr. 1, 1919.

Application filed November 16, 1917. Serial No. 202,394.

To all whom it may concern:

Be it known that I, CALEB C. REID, a citizen of the United States, residing at New Burnside, in the county of Johnson and State of Illinois, have invented new and useful Improvements in Railway-Crossing Signals, of which the following is a specification.

This invention relates to railway signals, and more especially to track instruments by means of which a circuit is closed by a passing train, so as to actuate a signal. In the present case this signal closes across a highway or other crossing, but it is obvious that the closing of the circuit could set or trip any kind of a signal or perform other necessary work.

Details appear in the following specification, reference being had to the drawings wherein:—

Figure 1 is a plan view of a section of single-track railway, with this invention applied at a point where the highway crosses the same.

Fig. 2 is a section through a pit adjacent to the highway crossing, and an elevation of the mechanism therein for closing the gate or signal.

Fig. 3 is an enlarged perspective detail of one rail of the track, showing the two members of the track instrument which becomes a circuit closer when depressed by the wheels of a passing engine or train.

Fig. 4 is an enlarged cross-section through one of the members and the circuit closer proper carried thereby, showing it in dotted lines as depressed so that the circuit closer contacts with the two wires.

Fig. 5 is a plan in diagram showing the action which takes place when the flange of a wheel passes the tongue at the inner end of one member and in between the rail and the tongue at the inner end of the companion member.

Fig. 6 is a perspective view of the wheel engaging shoe and

Fig. 7 is a diagrammatic view showing the electric circuit in which my device is arranged.

The primary object of the peculiar form of track instrument employed in this invention is to cause the closure of a circuit by a train approaching a given point. Herein said point is a highway crossing, and the closure of the circuit is employed to energize a motor which sets a gate or signal

across the highway, but it is obvious that the closed circuit could perform other work although doubtless it will be in the nature of setting a signal of some kind. After the train has passed said given point, or in other words when it passes off of one member of the track instrument and into engagement with the next, it rides outside the latter or between it and the rail and does not close the circuit because it does not depress the second member. Therefore so long as any wheel of the train which is approaching is engaged with the first member, the track instrument closes the circuit, but as soon as the last wheel has passed off the first member and onto the second member the circuit is broken and in the present case the signal starts to assume its "clear" position, but in any case the work performed by the closed circuit is over. Therefore this track instrument is serviceable with an engine or long train, moving in either direction.

In the accompanying drawings the letters R designate the rails of a track laid on ties T, and C is the highway crossing. The signal shown is a swinging arm or gate G which at night will carry lamps or lights L and which when it is depressed actuates a bell or alarm diagrammatically indicated by the letter A and connected up in some manner (not necessary to illustrate) with a source of power so that it will ring whenever the gate is lowered. The action of said gate is controlled by a motor M connected with the gate by gearing as illustrated and driven by electricity from a source of power such as a battery B, and the motor and battery are preferably located within a cement pit P adjacent the rails and highway and protected from weather or the interference of unauthorized persons. Wires W connect one side of the motor and one pole of the battery, and lead from the other side of the motor and the other pole of the battery along a considerable stretch of the track to both sides of the highway crossing C, and the construction is such that when a circuit is closed through these two wires, as by the actuation of the track instrument by a passing train, the battery drives the motor and the latter in turn closes the gate; whereas, when the circuit is again broken, a spring S (or it might be a weight or other device) again opens the gate and sets the signal at "clear."

With the signal and its operating mechanism as described above, I make use of an improved form of track instrument or circuit closer best illustrated in Figs. 3, 4, 5. 5 Adjacent one rail R stands two members or shoes 1 which are practical duplicates of and complementary to each other, and a description of one will suffice for both. Their contiguous ends are spaced from each other in 10 what I will call a "break" which in the present instance occurs adjacent the highway crossing C but preferably a little to one side of the same so that passing vehicles will not run over the break to the injury of the parts 15 yet to be described. In general, however, each member extends for a considerable distance from the highway alongside one rail, and it is immaterial which rail although in a two-track railway it might be well to lead 20 these members alongside the outermost rails. Each member or shoe 1 is of angle iron, and preferably L-shaped in cross-section as shown, its upright leaf 3 lying close to the inner face of the rail R and rising about 25 flush with the tread thereof, and preferably being lined on its outer face with insulation as at 4 so that it will not in any event come into contact with such rail and permit the charging of said shoe with a possible 30 current in the rail or the escape from the shoe to the rail of a current within the shoe. The horizontal leaf 5 of the shoe projects inward or away from the rail, and is disposed at such height that it will be 35 struck and the shoe depressed by the flange of a passing wheel which rides over this leaf. The shoe is supported at at least three points by springs 6, and for at least a portion of its length it carries on its under 40 side an inverted T-rail 7 whose shank is attached to the shoe in any suitable manner and whose head overlies the two wires W where the latter are bare. It follows that when the shoe is depressed said head is 45 thrown into contact with the wires and the latter are connected electrically so as to close a circuit through the battery and actuate the signal in the manner above described. By the word "depressed" I mean, however, that 50 the shoe must be decidedly depressed as would result from the pressure of the wheel-flange upon it when traveling over its horizontal leaf. I would have the springs so strong that cattle or malicious persons may 55 find it impossible to depress the shoe sufficiently to close the circuit. The upright leaf of each shoe carries at its outer end an outwardly deflected spring tongue 8 projecting toward the head of the rail and lined 60 on its outer face with insulation which normally contacts with said rail, and said leaf carries at its inner extremity an inwardly bent spring tongue 9 deflected away from the rail and not necessarily covered with the 65 insulation, the inner tongues 9 standing of

course at opposite sides of the break in the track instrument which is the space between its two members.

With this construction, the action of the forward wheel on the locomotive of an approaching train is as follows: The face of the wheel travels on the ball of the rail and its flange along the inner edge thereof, and when the flange reaches the outer end of either member of the track instrument it 70 passes inside the outwardly projecting tongue 8 and travels along the inner face of the upright leaf of the member, the edge of the flange meanwhile traveling upon the horizontal leaf thereof and depressing the 75 shoe so that its T-rail 7 makes contact with its wires W and closes the circuit to set the signal in the manner described. This action is duplicated by every succeeding wheel of the approaching engine or train, and the 80 member is of sufficient length to bridge the trucks in the longest car, and therefore the circuit is kept closed continuously during the approach of the train. Reaching the break or space in the instrument, the flange of the 85 foremost wheel rides past the inwardly projecting tongue 9 which yields to permit, then travels across the breaks, and passes between the corresponding tongue of the other member and the inner side of the rail, so that as 90 it continues on its course it moves this entire member slightly inward away from the rail, rather than depressing it, and yet it does not close electrical connection between the rail and the member because the latter 95 is insulated as described. Finally it passes the spring tongue 8 at the remote end of the second member, and onward along its way; and this action is followed by all succeeding wheels throughout the length of the train. 100 Thus it will be seen that as long as any truck overlies the member on the approaching side of the track instrument, the circuit is closed, but as soon as the last wheel has passed the break the circuit is again 105 opened and the spring S or other device may re-set the signal to a "clear" position as it may well do, because at this time the last car is about passing the crossing C. Obviously the same action would follow if the train 110 were passing in the other direction. Obviously also the signal would remain set at "danger", or closed if it be a gate as indicated at G, if the train should stop across the highway, provided only that at least one truck or 115 one wheel remained upon and depressed that member of the track instrument which may be said to be on the approaching side. Finally it is also obvious that the closure of the circuit may actuate any kind of a signal 120 or gate without departing from the principle of my invention.

What is claimed as new is:—

1. The herein described track instrument for railway signals and the like, the same 130

comprising two metallic members of L-iron spaced from each other at their contiguous ends, their upright leaves lying along the inner side of a rail and their horizontal leaves projecting inwardly and adapted to be depressed by the flange of a wheel passing over them, circuit-closing devices carried by said members and actuated by the depression thereof, and outwardly and inwardly deflected spring tongues at the respectively outer and inner ends of each member whereby the flange on the forward wheel of an approaching train passes over the first member reached and depresses it to close the circuit through said wires, and is directed between the rail and the second member reached so that the latter is not depressed.

2. A circuit closer for track instruments comprising a shoe of L-shaped cross-section whose upright leaf lies along the inner side of a rail and whose horizontal leaf projects inwardly and is adapted to be depressed by the flange of a passing wheel, insulation on the outer face of said upright leaf, circuit-closing devices proper carried by said horizontal leaf, and spring tongues at the extremities of the upright leaf, one deflected inward into normal contact with the rail and the other deflected in the opposite direction, for the purpose set forth.

3. A circuit closer for track instruments comprising a shoe of L-shaped cross-section whose upright leaf lies along the inner side of a rail and whose horizontal leaf projects inwardly and is adapted to be depressed by the flange of a passing wheel, insulation on the outer face of said upright leaf, circuit-closing devices proper carried by said horizontal leaf, spring tongues at the opposite ends of said upright leaf, one deflected inward toward the edge of the head of said rail and covered with insulation, and the other deflected in the opposite direction, for the purpose set forth.

4. A circuit-closing track instrument for railway signals and the like, the same comprising an inverted T-iron overlying a pair of spaced wires, a shoe of L-shaped cross-section whose upright leaf lies alongside a rail and is insulated on that face adjacent such rail and whose horizontal leaf projects inwardly away from the rail and carries the stem of said T-iron, springs yieldingly supporting said shoe with the T-iron normally out of contact with said wires, and spring tongues at the extremities of such upright leaf, one bent toward the rail and the other away from it, for the purpose set forth.

In testimony whereof I affix my signature.

CALEB C. REID.
